HINGED BACK COLLAPSIBLE CHAIR

Arthur A. Marks, Portland, Oreg.

Application April 8, 1946, Serial No. 660,368

4 Claims. (Cl. 155—148)

1

The present invention relates to improvements in chairs and more particularly to collapsible chairs. Occasions often exist when it is desirable to carry a chair about one's person in going from one place to another as to a picnic, ball game, and on an outing in general. It is necessary for such purposes to reduce the dimensions of the chair or seat so as to limit its bulk, make it compact, and render it fit to be carried around in the usual close quarters of a vehicle. This is the main purpose of my invention.

One of the objects thereof is to provide a collapsible chair all of the parts of which are shaped, arranged and caused to function in such a manner that they can be readily placed in erectable positions to properly assemble the back rest, seat and seat supporting sections of the chair, thereby setting it up for immediate use.

A further object thereof is to provide a dismanfleable chair having the desirable characteristics of sturdiness, foldability, rigidity in set up position, and compactness in knock down position.

A still further object thereof is to provide a knockdown chair with means for collapsing all the panels thereof in such a manner that they will all be surmounted overlappingly in a superimposed manner.

With the above and other objects in view, my invention consists in the combination, arrangement and details of construction disclosed in the drawings and specification and then more particularly pointed out in the appended claims.

In the drawings, wherein similar reference characters designate similar parts throughout the respective views.

Figure 1 is a side elevation of my invention.

Figure 2 is a front elevation thereof.

Figure 3 is a perspective view of my invention in a partially collapsed position.

Figure 4 is a cross-section taken on line 4—4 of Figure 1.

Figure 5 is a side view of a hook employed in latching parts of my invention and

Figure 6 is a fragmentary view of the back rest panel.

In the drawings, which are merely illustrative of my invention the various parts thereof are detailed.

The chair is composed of a seat, panel, a back rest panel and seat supporting side panels interconnected movably for collapsation one upon the other. The back rest panel 10, may be shaped so as to taper downwardly. For this purpose panel 10 will have oppositely inclining edges 11, 12. It will be formed with a hand gripping slot 13 at its upper end. A minor portion 14 of the length of panel 10 has an incut arcuate recess 15 formed at its lowermost edge to provide floor rests 16. The opposing side edges of portion 14 of panel

2

10 will preferably be parallel as at 17, 18. Where position 14 joins the major portion of the length of panel 10 right angular shoulders 19 are formed which form the edges 11, 12 or panel 10.

5 The seat panel of the chair is denoted at 26. Panel 26 is not as long as panel 10, extending the full length only of the major portion of length of panel 10. The upper corners of panels 10 and 26 may be rounded out as shown at A. Seat panel 26 is hinged at 29 to panel 10.

Back rest panel 10 is formed, beyond the lower or inner end of the seat panel 26 with a transverse arcuate edge 15 forming a concave face as shown in Figure 3. Spanning this face is a rod 20 which is secured at opposite ends by screws 21 directly to back rest panel portion 14, the extreme outer ends or terminals of rod 20 extend beyond the edges 17, 18 of the panel 10 where they are formed with pins 22 having heads 23.

20 These seat supporting panels 24, 25 are designed to be hinged in relation to seat panel 26 in such a manner that they may fold one on the other on their hinges 27 and 32 respectively in collapsed surmounted position on top of panel 26. For this purpose the hinges 27 are fastened to one of the margins of the seat panel 26 flush with the adjacent marginal edge. One marginal edge 26a of panel 24 is chamfered at opposite ends to provide recesses 26b in which hinge plates of 30 hinges 27 are secured. This construction assures that when panel 24 is folded in erect position its edge 26a will abut seat panel 26 and be held by the latter against further movement. In this way panel 24 will not, as it swings to open seat supporting position, swing over a greater arc than 90 degrees where it will depend at right angles from seat panel 26.

35 The other seat supporting panel 25 is not hinged directly upon seat panel 26. A piece 30, substantially the shape of a segment of a circle, is secured to a marginal position of the seat panel 26 in such a manner that its straight edge 19a (Figure 2) is flush with adjacent edge of seat panel 26, and its corner edge 31 extends inwardly. The hinges 32 secure panel 25 in the vicinity of the straight edge margin of piece 30 in such a manner that when panel 25 is folded up in erect perpendicular position upon seat panel 26 its upper edge will abut the panel 26, which assures that 45 panel 25 have no further swinging movement outwardly.

50 It will be seen that panel 24 is formed at its front edge with an arcuate edge 28, and is similarly formed upon its lower edge with a segmental recess and edge 31a which accurately matches the segmental edge 31 of piece 30. Panel 25 is also formed upon its front edge with segmental recess and edge 28a and upon its bottom edge with segmental edge 30a.

55 60 Seat supporting panels 24 and 25 are also

formed with coaxial elongated recesses 33, 34 respectively which open out of the rear edges thereof. A hook shank 35 has its journaling eye 36a secured by a fastener 36 upon panel 24 in the proper position to permit its hook bill 37 to extend into the plane of recess 33.

The use and operation of the collapsible chair is as follows: When it is desired to carry the chair about with all parts in convenient portable relationship, then folding will be accomplished as is illustrated in Figure 3. It will be seen that seat panel 26 has been folded back in surmounting position upon back rest panel 10. Panel 24 has been folded back in surmounted position upon seat panel 26. Panel 25 has been left unfolded to show segment-shaped piece 38. All of the parts being thus collapsed, they may be tied together so as not to open out. Rod 20 may easily be grasped by the hand inserted into view 15 of the back rest panel position 14, and handle like, permits the collapsed chair to be carried about conveniently.

When it is desired to erect all parts of the foldable chair into formation of a conveniently shaped chair or seat, the procedure will be as follows.

The seat supporting panels 24 and 25 will first be fully opened and made to abut seat panel 26. They will then be let down with the recesses bottom rest 16 upon the ground or floor so as to support the seat panel 26 in horizontal position. In order to prevent collapse of the seat supporting panels 24, 25 and also support back rest panel 10 in upright position, the back rest panel 10, will be tilted back on its hinges 29 to cause its minor rectangular portion 14 to project between the side panels 24, 25 as shown in dotted lines in Figure 1. In this position of panel 10, the opposing side edges of portion 14 thereof may abut panels 24 and 25. In this way panels 24, 25 will close against the edges of portion 14 of panel 10 so that they cannot move down or collapse upon their hinges 26 and 32.

A portion 14 of panel 10 moves inwardly between panels 24 and 25 the ends of rod 20 secured thereto are free to enter recesses 33, 34 of these panels, at the same time in such a manner that pintles 22 thereof will project beyond the faces of panels 24, 25.

The hook bills 37 will then be let down so as to engage around the pins 22 of rod 20 and be confined by the heads 32 of these pins. This assures that the back rest panel 10 of the chair will remain in a rigidly erect position, and that all panels comprising the collapsible chair are securely held in interconnected releasable position. It will be seen that when the panels are folded back into collapsed relation upon seat panel 26 that segmental edge 31a thereof will nicely coincide with segmental edge 31 on sector-shape piece 30. It will also be seen that shoulder 19 of panel 10 may be caused, as in Figure 2, to seat upon the top edges of panels 24 and 25.

I do not intend to limit myself to the exact details of construction disclosed in the drawings and specification herein but intend to cover all variations thereof.

What I desire to claim is:

1. A device as described consisting of oppositely arranged upright seat supporting panels formed with horizontal elongated recesses, a seat surmounting the top edges of said panels, a back rest movably mounted to said seat in surmountable relationship and having its lower portion

arranged to extend between said panels, studs carried by opposing edges of said lower portion of the back rest, entering said recesses and having annular grooves terminally, with complementary engaging hooks carried by said panels to latch said back rest erect upon said seat.

2. In a device as described, the combination of a back rest panel formed with a recess upon one end edge thereof, a rod spanning said recess, 10 being attached to said panel and having its opposite ends projecting beyond the side edges of the panel and formed with headed pins, a seat hingedly connected to said back rest panel, a seat supporting pair of oppositely arranged panels engageable with said back rest panel and hinged on said seat in a manner that said back rest panel may move from collapsed position to erect position to close said supporting panels upon opposing edges of said back rest panel, said seat supporting panels being formed with recesses opening out of their rear edges into which the ends of said rod project as said back rest panel moves into a position between said seat supporting panels, and hooks movably carried by said seat supporting panels engaging said pins to latch the back rest panel in erect position.

3. In combination a seat panel having a segment-shaped piece secured thereupon with its straight edge flush with one of the side edges of said panel, a pair of seat supporting panels having top edges hinged, respectively the first upon one margin of the seat and the second upon the straight marginal edge of the sector shaped piece, and having bottom edges formed with concave recesses, the first supporting panel swinging down in overlapping relation upon said seat with its concave recessed edge coinciding with the convex edge of said segment-shaped piece, the second supporting panel swinging down into overlapping position upon said first supporting panel and said sector shaped piece, and a prop hinged transversely along the rear edge of the seat so as to swing between said seat supporting panels for the purpose of spreading them apart.

4. In combination a seat having a pair of supporting panels arranged at opposite sides thereof, said panels formed with horizontal recesses upon their rear edges, a back rest panel having its major length extending above said seat in hinged relation and having a minor portion extending slidably between said supporting panels, oppositely arranged studs carried by the minor portion of said back rest panel designed to move into said recesses, and means on said seat supporting panels engaging said studs to hold the back rest panel in rigid upright position relatively to said seat.
